UNITED STATES PATENT OFFICE

OTTOKAR STERN, OF VIENNA, AUSTRIA

METHOD OF LAYING FOUNDATIONS OF STRUCTURES, BUILDINGS, AND THE LIKE

Original application filed January 21, 1926, Serial No. 82,792, now Patent No. 1,681,689, dated August 21, 1928, and in Austria January 24, 1925. Divided and this application filed December 22, 1926. Serial No. 156,492.

This invention relates to an improved method of laying foundations of structures, buildings and the like and essentially consists in that, according to a certain scheme, stand-
ardized foundation members of like shape and size are rammed into the ground to the same depth and thereafter, in accordance with the resistances met within the ground, a foundation member (differential member) of suitable length is sunk into the ground to such a depth, that, together with its group of standardized foundation members, it yields a total resistance, which is greater than the load of the building or structure accorded to this group of foundation members.

In this manner it is possible to produce foundations in the most simple manner, without any previous examination of the ground, because it is necessary only to suitably distribute individual foundation members (differential members) according to the experience gained when sinking the standardized foundation members.

One mode of carrying out the method according to the present invention is illustrated diagrammatically in the drawing:

Fig. 1 is a cross section showing applicant's invention in its relation to the surface of the ground. Fig. 2 is a plan view of Fig. 1. The dash-dotted line $m-n$ designates the extent of an ordinary wall-foundation and the steps show the different specific compressibility of the soil or of the different weights of the building. $a^1, a^2, a^3, a^4, a^5, a^6$ and a^7 are standardized foundation members, which are rammed into the soil, and $A^1, A^2, A^3, A^4, A^5, A^6$ and A^7 designate foundation members, which are sunk deeper into the ground according to requirement. R designates a grating, placed on top of the foundation members after the sinking into the ground of the latter and on which the building is erected.

A chart, calculated according to suitable ramming formulas, serves as an aid for carrying out the method and from this chart can be read off the degrees of penetration resistances encountered according to the weight of the ram and the lift thereof. For the sake of an easier understanding it is imagined, that the grating transfers the weight of the

building to three successive foundation members. However also a greater number of foundation members may be taken as the weight transferring group.

If for instance the penetration resistance, found during the sinking of the foundation member a^1 , corresponds to about two-thirds of the specific building-weight, which weight is termed that part of the weight lying in the space between two foundation members' axes. The second foundation member A^1 , which is again followed by a standardized foundation member a^1 , is sunk to such a depth, that five-third times the penetration resistance is obtained as in the event of the foundation member a^1 . In this manner the group of the cones a^1, A^1 and a^1 yields a total penetration re-

sistance, which equals $\frac{2}{3} + \frac{5}{3} + \frac{2}{3} = 3$ times

the specific building weight. Such groups are also formed by the foundation members $a^2, A^2, a^2; a^3, A^3, a^3; a^4, A^4, a^4$ and so forth. If the specific building weight increases in one group or if, in the event of the foundation soil getting worse, the penetration resistance is smaller, the compensating foundation member (differential member) is sunk deeper down into the ground.

I claim:—

1. A method of laying foundations of buildings, structures and the like, consisting in forming in the ground in a uniform depth and distance from one another standard-sized foundation members, and disposing differential foundation members at convenient places between the standard-sized foundation members and of such a depth as is necessary to supplement the total load carrying capacity of the group of members.

2. A method of laying foundations for superstructures consisting of driving foundation elements into the ground to a uniform depth and at uniform distances apart and in providing adjacent foundation elements in the ground of a load carrying capacity determined from the penetration resistance of the ground to the driving of the first named foundation elements and of a value whereby

the sum of the load carrying capacities of adjacent foundation elements is such as may be desired to support the load of the superstructure and provide a factor of safety.

- 5 3. A method of laying foundations for superstructures consisting in driving foundation elements into the ground to a uniform depth and at uniform distances apart, and in driving differential elements adjacent said first named foundation elements, said differential foundation elements having when driven in the ground a load carrying capacity determined from the penetration resistance of the ground to the driving of the first named foundation elements and of a value whereby the sum of the load carrying capacities of the adjacent foundation elements is such as may be desired to support the load of the superstructure and provide a factor of safety.
- 10 4. A method of laying foundations for superstructures consisting in ramming standard sized conical foundation elements directly into the ground for a uniform depth and at suitable distances apart, thereby compressing 25 and reinforcing the soil between the elements and applying a relatively thin grate plate at the surface for connecting the upper ends of the elements together so as to equally distribute the weight of the superstructure on the 30 foundation.
- 15 5. A method as claimed in claim 4, consisting in driving the standard sized foundation elements in groups which are disposed transversely of the plate and ramming a differential foundation element between each 35 group of standard sized elements for reinforcing purposes, and regulating the depth of the differential foundation elements to a point such as is necessary to supplement the 40 total load carrying capacity of the groups.
- 20 6. A method as claimed in claim 4, consisting in determining from the depth of the standard sized element the character of the soil being reinforced, and sinking differential 45 foundation elements between the standard sized foundation elements to such depth as is necessary to reinforce the standard sized elements and support the load of the superstructure.
- 25 7. A method as claimed in claim 4, wherein 50 the standard sized foundation elements are arranged very close to each other so that the grate plate has a thickness approximately equal to about one-half of the diameter of the 55 upper end of one of the standard sized foundation elements.
- 30 8. A method as claimed in claim 4, wherein 60 during the ramming of the standard sized foundation elements, a test is made for determining the carrying capacity of each point of the ground which is used for the foundation so that at each point of the ground a foundation of equal resistance is obtained.

In testimony whereof I affix my signature.

OTTOKAR STERN.
